SLEEVE-VALVE ENGINE

Application filed May 12, 1926. Serial No. 108,633.

It is the object of my invention to produce an internal combustion engine of the sleeve-valve type, and especially of the single-sleeve-valve type in which the sleeve has a combined 5 axial reciprocation and circumferential oscillation; but to locate the sleeve-valve or sleeve-valves in the cylinder heads, apart from the pistons, where they are both cooler and more readily coolable, are relieved from piston 10 ton drag, may be cooled by water passages within their cores, are at a more even temperature, have a less variation in temperature between their inner and outer surfaces, may have simpler driving mechanism, are 15 more accessible themselves and may have driving mechanism which is more accessible, may be removed without disturbing the pistons and permit the pistons to be removed without disturbing them or their operating 20 mechanism so that the sleeve-valve will be self-contained and may be assembled as a sub-unit, tested, and repaired apart from the rest of the engine, make the diameter and length of the sleeve independent of the diameter and stroke of the piston so that a variation 25 in one does not affect the other, make it unnecessary to locate complicated driving mechanism in the crank-case, make it possible to reduce the length and weight of the sleeve 30 or sleeves and thus both improve the balancing and reduce the frictional surface of the sleeve or sleeves so that there is less frictional loss and less difficulty in winter starting, and make it possible for one sleeve to control 35 the valving of a plurality of cylinders.

The objects of the present invention are generically the same as those set forth in my co-pending application Serial No. 125,248, filed July 27, 1926. In such co-pending application, certain specific illustrated embodiments of the invention common to that application and the present one involve having the axis or axes of the sleeve-valve or sleeve-valves in general transverse to the crank-shaft, so that in those specific embodiments there are independent sliding valves (such as sleeve-valves) for the different cylinders for any row of cylinders, so that claims to 45 separate sliding valves for different cylinders 50 and claims for the arrangement of the sleeve-

valves with their axes transverse to the crank-shaft as well as to the cylinder axis are presented in said co-pending application; whereas in the present application, the specific embodiments presented of such generic invention involve having the axis of the sleeve-valve in general parallel to the crank-shaft, so that the same sleeve-valve may control and usually does control a plurality of cylinders when the engine is a multi-cylinder engine 55 having a plurality of cylinders arranged in a row. Claims to these latter features are therefore presented in the present application; as are also claims to the generic invention. However, although the present application does show some modifications in which different sleeve-valves control different cylinders of a row of cylinders, as for instance Fig. 6, yet claims to an engine having a plurality of sleeve-valves are presented in said 60 co-pending application, and no such claims are presented in the present application because they would be alternative to other claims which are presented, and so are not 65 permissible in the present application. 70

In carrying out my invention, in its preferred form, I provide a sleeve-valve which extends transversely of the cylinder across the head thereof and controls the valving of the cylinder. This sleeve-valve is desirably a single-sleeve-valve, which has both an axial reciprocation and a circumferential oscillation; although my invention in its broader aspects does not prohibit the use of more than one sleeve, and does not require 75 the sleeve or sleeves to have both kinds of movement above referred to. The sleeve-valve or valves fit within a suitable transverse cylindrical bore in the cylinder head, and within the sleeve-valve or valves there is a suitable stationary core; so that the sleeve-valve or sleeve-valves move in an annular space between the core which they surround and the transversely bored head which surrounds them. Both this core and the head are conveniently water-cooled, and readily lend themselves to such cooling. The core is conveniently supported and piloted at its extreme ends, and so held in concentric position 80 within the sleeve-valve bore in the cyl- 85

inder head. The core preferably has transverse passages which co-operate with ports in the sleeve-valve or valves and with passages provided in the cylinder head surrounding the sleeve-valve and leading to the cylinders and to the intake and exhaust manifolds; so that a quadruple sealing may be provided. The sleeve-valve or valves are readily operated by mechanism which extends from the crank-shaft to such sleeve-valve or valves outside of the cylinders, and, if desired, wholly outside of the crank-case, so that the crank-case is left free from all sleeve-valve-operating mechanism. In the preferred form of my invention, which I have illustrated, the sleeve-valve or sleeve-valves extend along the row of cylinders of a multi-cylinder engine at the head ends of such cylinders, so that one sleeve valve controls the valving of a plurality of cylinders. In a multi-cylinder engine in which the cylinders are all arranged in a single row, one sleeve-valve may control the valving of all the cylinders of the engine; or there may be a plurality of sleeve-valves each controlling part of the entire number of engine cylinders, with the motion of these sleeve-valves arranged to produce a greater or less degree of balancing, especially in regard to their circumferential oscillation. If there is more than a single row of cylinders, as in V-type, W-type, X-type, or radial-type engines, the sleeve-valve or valves for a cylinder or cylinders arranged on one radius from the crank-shaft may be separate from the sleeve-valve or valves for the cylinder or cylinders on any other radius from the crank-shaft; but all these sleeve-valves for the various cylinders or rows of cylinders may still readily be operated by an operating mechanism which is separate from the cylinders and crank-case and which is in part common for the cylinders on all the different radii.

The accompanying drawings illustrate my invention: Fig. 1 is a vertical longitudinal section, in partial side elevation, of a four-cylinder internal combustion engine having a single controlling sleeve-valve in the head thereof for controlling the valving of all four cylinders; Fig. 2 is a vertical section on the line 2—2 of Fig. 1; Fig. 3 is an enlargement of the upper part of Fig. 2, but with the manifold connections removed, to show better the construction of the stationary core within the sleeve-valve and the passages within said core, the section being taken substantially on the line 3—3 of Fig. 4; Fig. 4 is a fragmentary section on the line 4—4 of Fig. 3; Fig. 5 is a section on the line 5—5 of Fig. 4, but with the operating shaft retarded 90°; Fig. 6 is a semi-diagrammatic view, showing my invention in connection with a six-cylinder engine, with the cylinders all in a single row, but with two sleeve-valves, each controlling half the total number of cylinders;

Fig. 7 is an end-elevation of a V-type engine, showing diagrammatically my invention in connection therewith, and indicating the drive for the sleeve-valves of the cylinders of the two rows; Fig. 8 is a fragmentary perspective view, with many parts broken away and some parts in section, of an X-type engine embodying my invention, with parts of the driving mechanism for the several sleeve-valves; Fig. 9 is a fragmental diagrammatic end elevation, to show the driving mechanism for the several sleeve-valves in the X-type engine of Fig. 8; Figs. 10 and 11 are development views of the upper and lower ports of the sleeve-valve and its associated stationary ports, as viewed from the top in both cases, for the four-cylinder engine shown in Figs. 1 to 5 inclusive; Fig. 12 is a development view of the lower port, as viewed from the top, for the six cylinder engine of Fig. 6; and Fig. 13 is a similar development view for a six-cylinder engine having a single controlling sleeve-valve for all six cylinders.

For simplicity in explanation, I will first describe my invention as applied to the four-cylinder engine illustrated in Figs. 1 to 5 inclusive.

The cylinders 10, shows as four in number in Fig. 1 although my invention is applicable to engines with any number of cylinders, are shown as having stationary liners 11; within which liners pistons 12 are reciprocable in the usual way. The liners 11 are not at all essential, and are shown merely as a desirable construction, as for instance when it is desired to make the cylinder block and crank-case of some non-ferrous metal, such as aluminum. These cylinders 12 are connected by connecting rods 13 to the cranks of a crank-shaft 14, which is located within a crank-case 15 which may be free from all valve-operating mechanism. Further, although my engine is a sleeve-valve engine, there is no sleeve-valve between any piston and its cylinder, and the pistons move within and against a stationary member, with purely axial relative motions between them, with no piston drag on or from a surrounding sleeve-valve. In consequence of this construction, the crank-case and cylinder block may be made in one piece if desired, which is not practicable with types of sleeve-valve engines having the sleeve-valves surrounding the pistons.

The upper end of the cylinder block may be faced off flat, with counter bores if desired for receiving flanges 16 provided at the upper end of the liners 11 to hang them. On this flat top of the cylinder block, I attach a head 20, which is illustrated as a single head extending along the entire cylinder block. This cylinder head is attached to the cylinder block by suitable studs and nuts 21, or in any other convenient way.

This cylinder head 20 is provided with a longitudinal bore, generally cylindrical,

which extends along its whole length. Within this cylindrical longitudinal bore, and having a snug sliding fit therewith, is my sleeve-valve or valves 25. This sleeve-valve 5 is desirably a single-sleeve-valve, as distinguished from two concentric sleeve-valves as in the Knight type of engine; although my invention is not limited to the use of a single-sleeve-valve as distinguished from a 10 double-sleeve-valve. The sleeve-valve 25 consists of a single tube, as will hereinafter be more fully described, and is reciprocable axially and oscillatable circumferentially in a closed curved path, which will also be explained later. This sleeve-valve may be made quite thin, so that the reciprocating and oscillating weight is very small.

To obtain this composite movement of the sleeve-valve 25, I desirably use the construction 20 which is shown more in detail in Figs. 4 and 5, although it is also indicated in Figs. 1 and 2. In this construction, I apply the moving force to the sleeve-valve 25 at one end thereof, at which end I provide a reinforcing band 26, thickened at one part of its circumference to carry the socket member 27 of a ball-and-socket joint. The band 26 is desirably riveted to the sleeve-valve, although it may be attached thereto in any 30 other suitable way. The ball member 28 of the ball-and-socket joint is provided on the end of a cylindrical pin 29, which has a 35 slideable mounting along its own axis in a hole eccentrically located in a counter-weighted head 31 on the end of a shaft 32. The counter-weight on the head 31 is a balancing weight, which may be made to balance to a greater or less extent the forces created by the motion of the sleeve-valve. Thus the 40 pin 29 is in effect a crank-pin on the shaft 32, although it is slideable axially of such shaft 32 as required by the turning of the sleeve-valve 25 about its axis. The center of the ball-and-socket joint 27-28 is closer to 45 the inner surface of the sleeve-valve itself than the diameter of such joint; which is rendered possible by having the ball member 28 a mere spherical segment. This spherical segment forming the ball member 28 is removably attached to the pin 29, as by a cap-screw 33; so that by removing the cap-screw 33 and withdrawing the pin 29 from the ball member, the latter may be turned from its normal working position to bring suitable 55 cut-away faces 34 of the ball member into proper position to permit such ball member to be removed from the socket member. The lower end of the pin 29 is desirably provided with a screw-driver slot to turn it while holding the cap-screw 33. The pin 29 is withdrawn from its hole when the cylinder head and sleeve-valve are removed as a unit; and is mounted in such hole when such unit is put on the cylinder block. All this facilitates 60 assembling and dismantling.

The shaft 32 is suitably driven from the crank-shaft 14, through any convenient form of drive, and operates at half crank-shaft speed. To this end, in the preferred construction, the shaft 32 extends from its sleeve-valve end (the upper end in Figs. 1 to 5 inclusive) into proximity with the crank-shaft, and is there connected to the crank-shaft through suitable gearing 35, conveniently spiral gearing. The gearing 35 and the shaft 32 are desirably located in a special compartment 36 in the engine housing, at one end of the row of cylinders 10; and this compartment 36 is desirably entirely separate from the space within the crank-case itself. 70 To accommodate the spiral gearing 35, the shaft 32 is slightly oblique with respect to the cylinder axes, as is clear from Figs. 2 and 5, but is conveniently radial to the sleeve-valve.

By the rotation of the crank-shaft 14, and the consequent rotation of the shaft 32 at half crank-shaft speed, the ball member 28 travels around the axis of the shaft 32; and in so doing it gives the sleeve-valve 25 the desired circumferential oscillation and longitudinal reciprocation. The center of the ball-and-socket joint 27-28 is desirably so located with respect to the axis of the sleeve-valve that the arcuate length of circumferential oscillation is substantially equal to the length of axial reciprocation; as that makes the development of the path of travel of any point on the sleeve-valve substantially a circle, which has certain advantages in the design and location of the ports.

The sleeve-valve 25 is not only supported exteriorly by the wall of the bore in the cylinder head, but is supported interiorly by a stationary core 40, which extends the entire length of the sleeve-valve. This core 40 has at one end, the right-hand end in Fig. 1, both a pilot enlargement or collar 41 snugly fitting in the bore of the cylinder head to locate the core concentrically to the bore at that end and an outwardly extending flange 42 by which that end of the core may be bolted to the cylinder head 20 by suitable cap-screws 43. At its other end, the left-hand end in Figs. 1 and 4, the core 40 has a sliding fit in a spacing ring 44 removably mounted in the end of the cylinder head 20, which support effectively centers this end of the core 40 but permits such end to move lengthwise relatively to the corresponding end of the cylinder head if any tendency to such movement arises by reason of differential thermal expansion. By the removal of the spacing ring 44, the sleeve-valve 25 itself may be put into place or withdrawn, with its band 26 and its ball-and-socket joint 27-28, the pin 29 of course being separated from the ball member 28 during such insertion or withdrawal. The supporting metal for the spacing ring 44 may be cut away at one point both internally and 130

externally to permit the passage of the socket member 27 and the band-enlargement in which it is mounted.

The core 40 is generally hollow, to constitute a passageway for the circulation of the cooling medium, which is usually water. When water is the cooling medium, the cylinders 10 and the cylinder head 20 are provided with suitable water passages 45 and 46, 10 suitably arranged to intercommunicate as is usual in engine design. At the right-hand end (Fig. 1) of the cylinder head there is a closing cap 47, which covers the cap-screws 43 and provides a communication between the 15 water-passages 46 in the cylinder head and the interior of the core 40. At the left-hand end (Fig. 1) of the cylinder head, there is a pipe connection 48 which overlaps the end of the cylinder head and also extends partly 20 along one side thereof, to communicate both with the water-passages 46 of the cylinder head and with the end opening of the core 40, so that water from both passages may reach such connection 48 and pass there- 5 through to the top of the usual radiator which is provided in a water-circulating system. The remainder of the water-circulating system is not shown, as it may be anything desired.

30 Although the core 40 is generally hollow, it is not completely so; but has various walls 50 in it to provide passages through the core for the inlet and exhaust gases. These passages register at the top with suitable inlet 35 ports 51 and exhaust ports 52, provided in the cylinder head at the top; and the inlet and exhaust ports 51 and 52 communicate respectively with a suitable inlet manifold 53 and a suitable exhaust manifold 54. The 40 passages in the core register at the bottom with suitable inlet and exhaust ports for the various cylinders 10, which cylinder ports will be described more fully later, as will also the passages provided by the walls 50 within 45 the core 40. The sleeve-valve 25 in the engine of Figs. 1 to 5 has ports through it to control the opening and closing of both ends of the passages through the core, so that there may be a double valving action between a cylinder 50 and a manifold, on the upper and lower sides of the core 40, and a quadruple sealing surface may thus be provided by the internal and external surface of the sleeve-valve on both the upper side and the lower side thereof. 55 Such a quadruple sealing is shown for the exhaust passages of the end cylinders.

One suitable port arrangement for the sleeve-valve and its associated stationary members is shown in Figs. 10 and 11 for a 60 four-cylinder engine such as is illustrated in Figs. 1 to 5 inclusive. As is evident from Figs. 1 and 10, in that illustrative arrangement, (which is not at all an essential arrangement,) the series of ports 51—52 in the 65 cylinder head above the sleeve consists of

five ports, of which the first, third, and fifth are exhaust ports communicating with the exhaust manifold 54, and the second and fourth are inlet ports communicating with the inlet manifold 53. Directly below the 70 ports 51 and 52 in the top of the head are respectively registering ports at the upper ends of inlet passages 61 and exhaust passages 62 provided by the walls 50 in the stationary 75 core 40. The passages 61 and 62 are deflected in suitable ways as they pass through the core so that at their lower ends they provide core ports which correspond with and register with one or more inlet ports 63 and one or more exhaust ports 64 for each cylinder 10. 80 In the preferred arrangement, I provide two inlet ports 63 and two outlet ports 64 for each cylinder, and arrange these four ports substantially at the corners of a square on the development of the cylindrical surface; 85 which is rendered possible by having the arcuate length for circumferential oscillation substantially equal to the length of axial reciprocation of the sleeve-valve. With that arrangement of ports, the ports 63 and 64 for all the cylinders of the engine may be substantially alike, but merely turned to different positions on the circular path of movement of any point on the sleeve-valve, to correspond with the firing order and the number 90 of cylinders of the engine. In the four-cylinder engine shown in Figs. 1 to 5, 10, and 11, where the firing order is 1—2—4—3, the arrangement of the ports 63—64 may be taken as normal for cylinder No. 1, and as turned 95 90° from that position for cylinder No. 2, 180° from that position for cylinder No. 4, and 270° from that position for cylinder No. 3, measuring the angles in the direction of movement of any point on the sleeve-valve in 100 the circular travel of such point.

The ports 51, 52, 63, and 64 in the cylinder head and the corresponding ports at the upper and lower ends of the passages 61 and 62 through the core are stationary, but they 105 co-operate with suitable movable ports 65 in the upper half of the sleeve-valve 25 and with suitable movable ports 66 in the lower half of the sleeve-valve 25. The ports 65 travel in circular paths, in the preferred construction shown, to control the stationary ports 51 and 52; and the ports 66 travel in corresponding circular paths to control the stationary ports 63 and 64. The directions in 110 which these movable ports 65 and 66 are traveling are illustrated by short curved arrows in Figs. 10 and 11, the engine being assumed to be directly at the dead-center firing point for cylinder No. 1; and the arrows appear 115 differently in Figs. 10 and 11 because both are development views as seen from above, which makes the upper and lower ports of the sleeve-valve and therefore the upper and lower ports 65 and 66 appear as moving in 120 opposite directions in corresponding circles. 125

The ports 51 and 52 may be circular ports, and the ports 65 may then be correspondingly circular. Some of the ports 65 are double ports, as shown by the second port 65 from each end in Fig. 10, in which case they are 5 not circular but are really two overlapping circles with the cups between flattened down.

In order to get quick opening and closing movements, however, I prefer that at least 10 the ports 63, 64, and 66 be made to have their opening and closing edges substantially perpendicular to the direction of movement as such edges co-operate to open or close the ports. The advantage of such quick opening and closing is well understood. Therefore, 15 the ports 63, 64, and 66 are shown as generally triangular in shape, to get edges which give this action.

In the porting arrangement shown in Fig. 20 11, the inlet ports 63 close, and the exhaust ports 64 open by substantially lengthwise movement of the sleeve-valve for the end cylinders 1 and 4 and by substantially circumferential movement for the intermediate cylinders 2 and 3. This is merely incidental, 25 however, as the ports may be arranged to reverse this; as is indeed illustrated in Fig. 12, (described later,) where such port action is by substantial lengthwise movement of the 30 sleeve-valve for the two middle cylinders.

When the engine is a six-cylinder engine, with one sleeve-valve controlling all six cylinders, the arrangement of ports may be as 35 illustrated in Fig. 13. Here the firing order is assumed to be 1-5-3-6-2-4; and the ports 63, 64, and 66 for any cylinder are then turned corresponding angles in their arrangement on the circular path of travel of any point on the sleeve-valve, the ports for cylinder 5 being turned 60°, those for cylinder 40 6 being turned 120°, those for cylinder 3 being turned 180°, those for cylinder 2 being turned 240°, and those for cylinder 4 being turned 300° from what may be called the zero position in which the ports for cylinder 45 No. 1 are shown.

In order to get the ports 63, 64, and 66 in a 50 small space, so that the diameter of the circular path of travel of any point on the sleeve-valve may be as small as possible for a given port opening, it is sometimes necessary to distort slightly the shape of some of the ports. This is shown for one of the exhaust ports 64 for each of the cylinders in Figs. 11 and 13. 55 This is merely to prevent that distorted port from being overlapped at any time by a corner of the movable port 66 with which it is not intended to co-operate.

With the arrangement of ports which has 60 been described, there may be a quadruple sealing action between the cylinder and a manifold. In other words, there may be a sealing by the inner and outer surfaces of the sleeve-valve for the lower half of such sleeve-valve in connection with the ports 63 or 64,

and 66, and another sealing at both the inner and outer surfaces of the sleeve-valve for the upper half of such sleeve-valve in connection with the ports 51 or 52, and 65. This quadruple sealing is found to be most effective. It 70 is not essential to my broad invention, however, and I have shown it only for the exhaust of the end cylinders, cylinders 1 and 4, in the porting arrangement illustrated in Figs. 10 and 11.

Instead of having one sleeve-valve which 75 controls all the cylinders of a row of cylinders, such as four, six, or eight cylinders in a row, it is sometimes desirable to provide two sleeves, each controlling half of the entire 80 number of cylinders as located on one side of the middle of the row of cylinders. This is illustrated in Figs. 6 and 12, which show a six-cylinder engine having one sleeve controlling 85 the three cylinders toward one end of the row of cylinders, and a separate sleeve controlling the three cylinders toward the other end of such row. The two sleeve-valves 25^a and 25^b may conveniently be driven by the 90 mechanism shown in Fig. 6, where there are two shafts 32^a and 32^b connected to the ends of the respective sleeve-valves in the manner already described for the shaft 32 of Figs. 1, 4, and 5, the shafts 32^a and 32^b being connected by spiral gearing 35^a and 35^b respectively to a 95 common countershaft 70 suitably driven from the crank-shaft 14, as by a chain drive 71. The timing is desirably such that the sleeve-valves 25^a and 25^b move axially together toward 100 one end or the other, but oscillate angularly in opposite phases, so that for the angular oscillation there is a balancing action between the two sleeve-valves. The ports in and 105 controlled by the sleeve-valves 25^a and 25^b are not indicated in Fig. 6, as that figure is semi-diagrammatic, but the ports 63, 64, and 66 are in general like those already described bearing similar reference numbers, and are 110 illustrated in the development view of Fig. 12.

So far I have described my invention as 115 applied to engines in which all cylinders are in a single row. However, my invention is equally applicable to various other types of engines. I have shown two other types in Fig. 7 and Figs. 8 and 9 respectively.

In Fig. 7, I show my invention, diagrammatically, as applied to a V-type engine. Here there are two rows of cylinders 10^c and 10^d, at an angle to each other, and these rows of cylinders are controlled respectively by 120 sleeve-valves 25^c and 25^d respectively. These sleeve-valves correspond in general to the sleeve-valve 25 already described, and have 125 similar co-operating parts; so that they operate to control their respective rows of cylinders in a manner which has already been made plain.

A simple way of driving the two sleeves 25^c and 25^d is illustrated in Fig. 7. Here the 130 crank-shaft 14 is connected by bevel gearing

72 to a shaft 73, which in turn is connected through spiral gearing 74 to a cross shaft 75 which extends perpendicularly to and between the two sleeves 25^a and 25^b. Each of 5 such sleeve-valves is connected to the adjacent end of the cross-shaft 75 by connecting mechanism which is substantially like that which has already been described as connecting the sleeve-valve 25 to the adjacent end of the shaft 32. By the sleeve-valve arrangement of 10 Fig. 7, I may obtain a balancing both axially and circumferentially of the sleeve valves.

In Figs. 8 and 9 I show my invention as applied to an X-type of engine. In that type of 15 engine there are four rows of cylinders 10^a set on different radii from the common crank-shaft 14. At the outer or head ends of each row of cylinders 10^a, there is a sleeve-valve 25^b, which in general may be like the sleeve-valve 25 already described. Each of these 20 sleeves 25^b is driven from a shaft 32^b by mechanism similar to that already described as connecting the shaft 32 to the sleeve-valve 25; and the shafts 32^b may all be driven from the 25 crank-shaft 14 by spiral gearing 35 such as has already been described, the difference being that the spiral gear on the crank-shaft 14 meshes in common with the spiral gears on all the shafts 32^b, as is clear from Fig. 9.

30 In the arrangement shown in Fig. 8, I illustrate a further modification, in two respects. First, the core within the sleeve-valve is open at its ends for air cooling by a lengthwise flow of air through it as this 35 engine is shown as an air-cooled engine. Second, the sleeve-valve controls only by ports in its side toward the cylinders (the lower side as illustrated), and the manifolds are arranged within the hollow core, only the 40 exhaust manifold 54^a being illustrated in the section. This gives only a simple valving and only a double sealing, but is within the broad scope of my invention.

The sleeve-valves and their driving mechanism may be lubricated in any suitable manner. I have shown one lubricating arrangement in Figs. 1 to 5. In that arrangement, there is an oil pump 80, which pumps oil from the oil pan 81 through a pipe 82 to one 45 or both bearings 83 for the shaft 32 and to suitable oil-inlet holes 84 along the bore for the sleeve-valve 25. The points for the oil-inlet holes 84 on the sleeve-valve bore are chosen so that such holes are never overlapped by any sleeve-valve ports; and at 50 these points the sleeve-valves may have holes 86 through them to let oil pass through to a distributing groove 87 on the surface of the core 40. The shaft 32 may have an oil hole 88 connecting the bearing surface at the upper bearing 83 and the hole for the pin 29.

The precise structure shown in the drawings are merely illustrative of my invention, for such invention is capable of many variations from the structures shown. For in-

stance, my invention is applicable to many other types of engines than the straight-line type, V-type, and X-type shown; each sleeve-valve may control all or any desired part of the entire number of engine cylinders, and in the broader aspects of my invention any sleeve-valve need not control more than a single cylinder; the axes of the sleeve-valve or sleeve-valves need not necessarily extend along a row of cylinders, although that is 70 the preferred construction and is illustrated in all the modifications shown; the sleeve-valve driving mechanism may take any suitable form, that shown being merely an illustrative form which is quite effective; and the 75 sleeve-valve control is not limited to single-sleeve valves.

I claim as my invention:—

1. An internal combustion engine, comprising a cylinder having a cylinder head, a piston reciprocable in said cylinder, a core having a passage, a sleeve-valve mounted in the cylinder head and around said core and controlling the connection between said passage and a port of said cylinder, and means for driving said sleeve-valve with a combined axial reciprocation and circumferential oscillation so that any point thereon travels in a closed curved path. 85

2. An internal combustion engine, comprising a cylinder having a cylinder head, a piston reciprocable in said cylinder, a core having a passage, a sleeve-valve mounted in the cylinder head on an axis transverse to the cylinder axis, said sleeve-valve being mounted around said core and controlling the connection between said passage and a port of said cylinder, and means for driving said sleeve-valve with a combined axial reciprocation and circumferential oscillation so that any 90 point thereon travels in a closed curved path. 100

3. An internal combustion engine, comprising a cylinder, having a cylinder head, a piston reciprocable in said cylinder, a core having open space within it, a sleeve-valve mounted in the cylinder head and around said core and controlling the connection between the ports of said cylinder and open space within said core, and means for driving said sleeve-valve with a combined axial reciprocation and circumferential oscillation so that any point thereon travels in a closed curved path. 110

4. An internal combustion engine, comprising a cylinder having a cylinder head, a piston reciprocable in said cylinder, a core having open space within it, a sleeve-valve mounted in the cylinder head on an axis transverse to the cylinder axis, said sleeve-valve being mounted around said core and controlling the connection between the ports of said cylinder and open space within said core, and means for driving said sleeve-valve with a combined axial reciprocation and circumferential oscillation so that any point thereon travels in a closed curved path. 120

cumferential oscillation so that any point thereon travels in a closed curved path.

5. A multi-cylinder internal combustion engine, comprising a plurality of cylinders arranged in a row, pistons movable in the respective cylinders, and a sleeve-valve free of cross-tubes and mounted in the head of the cylinders and extending along the row of cylinders and controlling a port or ports of one of said cylinders, said sleeve-valve having a combined axial reciprocation and circumferential oscillation so that any point thereon travels in a closed curved path.

6. A multi-cylinder internal combustion engine, comprising a plurality of cylinders arranged in a row, pistons movable in the respective cylinders, and a sleeve-valve free of cross-tubes and mounted in the head of the cylinders and extending along the row of cylinders and controlling a port or ports of each of a plurality of said cylinders, said sleeve-valve having a combined axial reciprocation and circumferential oscillation so that any point thereon travels in a closed curved path.

7. A multi-cylinder internal combustion engine, comprising a plurality of cylinders, pistons movable in the respective cylinders, and a sleeve-valve having a combined axial reciprocation and circumferential oscillation so that any point thereon travels in a closed curved path and controlling the ports of a plurality of the cylinders of said engine, said sleeve-valve being free of cross-tubes.

8. An internal combustion engine, comprising a cylinder, a piston, and a sleeve-valve having a combined axial reciprocation and circumferential oscillation so that any point thereon travels in a closed curved path and controlling a port of said cylinder to produce a quadruple sealing of such port when it is closed.

9. An internal combustion engine, comprising a cylinder, a piston reciprocable therein, a sleeve-valve mounted in the cylinder head, said sleeve-valve having a combined axial reciprocation and circumferential oscillation so that any point thereon travels in a closed curved path, and a core within said sleeve-valve, said core having transverse passages through it for the inlet and exhaust gases, which passages at one end communicate with ports in the cylinder head leading to the cylinder and at the other end with ports of inlet and exhaust passages, and said sleeve-valve being provided with openings which by the movement of the sleeve-valve control the opening and closing of both ends of said passages through the core.

10. In an internal combustion engine, a cylinder, a piston, a sleeve-valve having a combined axial reciprocation and circumferential oscillation so that any point thereon travels in a closed curved path and controlling a port of said cylinder and located

apart from said piston with its axis at an angle to the cylinder axis, and a core around which said sleeve-valve fits and which has within it a space whose connection to said cylinder port is controlled by the movements of said sleeve-valve.

11. In an internal combustion engine, a cylinder, a piston, and a sleeve-valve free of cross-tubes and controlling the ports of said cylinder and located apart from said piston with its axis at an angle to the cylinder axis, said sleeve-valve being a single-sleeve-valve having a combined reciprocating and oscillating motion.

12. In an internal combustion engine, a cylinder, a piston, a sleeve-valve having a combined axial reciprocation and circumferential oscillation so that any point thereon travels in a closed curved path and controlling a port of said cylinder and located apart from said piston with its axis at an angle to the cylinder axis, and a stationary core within said sleeve-valve, said core being provided with transverse passages which form part of the inlet and exhaust conduits for said cylinder, and said sleeve-valve being arranged to control said core passages at both ends thereof.

13. In an internal combustion engine, a cylinder, a piston, a sleeve-valve controlling the ports of said cylinder and located apart from said piston with its axis at an angle to the cylinder axis, said sleeve-valve being a single-sleeve-valve having a combined reciprocating and oscillating motion, and a stationary core within said sleeve-valve, said core being provided with transverse passages which form part of the inlet and exhaust conduits for said cylinder, and said sleeve-valve being arranged to control said core passages at both ends thereof.

14. An internal combustion engine, comprising a cylinder, a piston reciprocable therein, a sleeve-valve mounted in the cylinder head, said sleeve-valve having a combined axial reciprocation and circumferential oscillation so that any point thereon travels in a closed curved path, and a core within said sleeve-valve, said core having transverse passages through it for the inlet and exhaust gases which passages at one end communicate with ports in the cylinder head leading to the cylinder and at the other end with ports of inlet and exhaust passages, and said sleeve-valve being provided with openings which by the movement of the sleeve-valve control the opening and closing of at least one end of said passages through the core.

15. In an internal combustion engine, a cylinder, a piston, a sleeve-valve having a combined axial reciprocation and circumferential oscillation so that any point thereon travels in a closed curved path and controlling a port of said cylinder and located apart from said piston with its axis at an angle to the cylinder axis.

axis, and a stationary core within said sleeve-valve, said core being provided with passages which form part of the inlet and exhaust conduits for said cylinder, and said sleeve-valve being arranged to control said core passages.

16. In an internal combustion engine, a cylinder, a piston, a sleeve-valve controlling the ports of said cylinder and located apart from said piston with its axis at an angle to the cylinder axis, said sleeve-valve being a single-sleeve-valve having a combined reciprocating and oscillating motion, and a stationary core within said sleeve-valve, said core being provided with passages which form part of the inlet and exhaust conduits for said cylinder, and said sleeve-valve being arranged to control said core passages.

17. An internal combustion engine, comprising a cylinder having a cylinder head, a piston reciprocable in said cylinder, a core having open space within it, a sleeve-valve mounted in the cylinder head and around said core and controlling the connection between the ports of said cylinder and open space within said core, and means for driving said sleeve-valve with a combined axial reciprocation and circumferential oscillation so that any point thereon travels in a closed curved path with the length of axial reciprocation substantially equal to the arcuate length of circumferential oscillation.

18. A multi-cylinder internal combustion engine, comprising a plurality of cylinders, pistons movable in the respective cylinders, a single-sleeve-valve having a combined axial reciprocation and circumferential oscillation so that any point thereon travels in a closed curved path and controlling the ports of a plurality of the cylinders of said engine, and a core around which said single-sleeve-valve fits and which has within it separated passages for the intake and exhaust gases.

19. A multi-cylinder internal combustion engine, comprising a plurality of cylinders, a sleeve-valve having a combined axial reciprocation and circumferential oscillation so that any point thereon travels in a closed curved path, and controlling ports of said cylinders, said sleeve-valve being located apart from said pistons with its axis at an angle to the cylinder axes, and a stationary core within said sleeve-valve, said core being provided with transverse passages which form part of the inlet and exhaust conduits for cylinders of said engine, and said sleeve-valve being arranged to control said core passages at both ends thereof.

20. A multi-cylinder internal combustion engine, comprising a plurality of cylinders, pistons movable in said cylinders, a sleeve-valve having a combined axial reciprocation and circumferential oscillation so that any point thereon travels in a closed curved path, said sleeve-valve being located apart from said pistons with its axis at an angle to the

cylinder axes, and a stationary core within said sleeve-valve, said core being provided with passages which form part of the inlet and exhaust conduits of said engine, and said sleeve-valve being arranged to control the communication between said core passages and the respective cylinders.

21. A multi-cylinder internal combustion engine, comprising a plurality of cylinders, pistons movable in the respective cylinders, a sleeve-valve having a combined axial reciprocation and circumferential oscillation so that any point thereon travels in a closed curved path, said sleeve-valve being located apart from said pistons with its axis at an angle to the cylinder axes, and a stationary core within said sleeve-valve, said core being provided with one or more passages which form part of a conduit which communicates by said passage or passages with ports of said cylinders, and said sleeve-valve being arranged to control the communication between said core passage or passages and parts of said cylinders.

22. An internal combustion engine, comprising a cylinder, a piston, a crank-shaft, a sleeve-valve having its axis generally parallel to the crank-shaft and being arranged to have a combined axial reciprocation and circumferential oscillation so that any point thereon travels in a closed curved path, a stationary core within said sleeve-valve, said core being provided with one or more passages, and said sleeve-valve being arranged to control the communication between said core passage or passages and one or more parts of said cylinder.

23. An internal combustion engine, comprising a cylinder having a port or ports, a piston movable therein, a valving member having parallel inner and outer curved valving surfaces each equi-distant at all points from a common axis which is apart from the cylinder axis, and means for moving said valving member so that it has a combined axial reciprocation along said axis and arcuate oscillation about such axis, said valving member being arranged to control a port or ports of said cylinder.

24. A multi-cylinder engine, comprising a plurality of cylinders each having a port or ports, pistons movable in the respective cylinders, a valving member having parallel inner and outer curved valving surfaces each equi-distant at all points from a common axis which is apart from the axis of any of the cylinders, and means for moving said valving member so that it has a combined axial reciprocation along said axis and arcuate oscillation about such axis, said valving member being arranged to control a port or ports of each of a plurality of the cylinders of the engine.

25. A multi-cylinder engine, comprising a plurality of cylinders each having a port or ports, pistons movable in the respective cylinders, a valving member having parallel

inner and outer curved valving surfaces each equi-distant at all points from a common axis, and means for moving said valving member so that it has a combined axial reciprocation along said axis and arcuate oscillation about such axis, said valving member being arranged to control a port or ports of each of a plurality of the cylinders of the engine.

26. In an internal combustion engine, a cylinder, a piston, a sleeve-valve mounted in a suitable bore in the cylinder head, and a removable stationary core fitting within said sleeve-valve, said core being concentrically piloted within said bore at at least one end.

27. In an internal combustion engine, a cylinder, a piston, a sleeve-valve mounted in a suitable bore whose axis is apart from the cylinder axis, and a stationary core fitting within said sleeve-valve, said core being concentrically piloted within said bore at each end.

28. In an internal combustion engine, a cylinder, a piston, a sleeve-valve mounted in a suitable bore whose axis is at an angle to the cylinder axis, and a stationary core fitting within said sleeve-valve, said core being concentrically piloted within said bore at at least one end.

29. In an internal combustion engine, a cylinder, a piston, a sleeve-valve mounted in a suitable bore in the cylinder head, and a stationary core fitting within said sleeve-valve, said core being mounted so that the sleeve-valve is removable and replaceable without disturbing the core.

30. In an internal combustion engine, a cylinder, a piston, a sleeve-valve mounted in a suitable bore whose axis is apart from the cylinder axis, and a stationary core fitting within said sleeve-valve, said core being concentrically piloted within said bore at both ends and mounted so that the sleeve-valve is removable and replaceable without disturbing the core.

31. In an internal combustion engine, a cylinder, a piston, a sleeve-valve mounted in a suitable bore in the cylinder head, and a stationary core fitting within said sleeve-valve, said core being concentrically piloted within said bore at both ends and mounted so that either the core or the sleeve-valve may be separately removed endwise without disturbing the other.

32. In an internal combustion engine, a cylinder, a piston, a sleeve-valve mounted in a suitable bore whose axis is apart from the cylinder axis, and a stationary core fitting within said sleeve-valve, said core being concentrically piloted within said bore at both ends and mounted so that either the core or the sleeve-valve may be separately removed endwise without disturbing the other.

33. In an internal combustion engine, a cylinder, a piston, a sleeve-valve mounted in a suitable bore in the cylinder head, a sta-

tionary core fitting within said sleeve-valve, said sleeve-valve being formed of plain tubing with suitable port openings in it and a reinforcing member attached to said tubing at a power-receiving point, and means acting on said sleeve-valve at said reinforcement for producing a combined axial reciprocation and circumferential oscillation of said sleeve-valve.

34. In an internal combustion engine, a cylinder, a piston, a sleeve-valve mounted in a suitable bore whose axis is apart from the cylinder axis, a stationary core fitting within said sleeve-valve, said sleeve-valve being formed of plain tubing with suitable port openings in it and a reinforcing member attached to said tubing at a power-receiving point, and means acting on said sleeve-valve at said reinforcement for producing a combined axial reciprocation and circumferential oscillation of said sleeve-valve.

35. In an internal combustion engine, a cylinder, a piston, a sleeve-valve having a combined axial reciprocation and circumferential oscillation so that any point thereon travels in a closed curved path, said sleeve-valve being arranged to control both the inlet and exhaust of the cylinder, said sleeve-valve having two double-purpose ports, and a stationary part co-operating with said sleeve-valve having a pair of inlet ports and a pair of exhaust ports for said cylinder, the lines of said inlet and exhaust ports being displaced from each other, each double-purpose port in the sleeve-valve being arranged to co-operate successively with one port of each of said two pairs of stationary ports without interfering with the other port of either of said pairs of ports.

36. In an internal combustion engine, a cylinder, a piston, and a sleeve-valve having a combined axial reciprocation and circumferential oscillation so that any point thereon travels in a closed curved path, said sleeve-valve being arranged to control both the inlet and exhaust of the cylinder, said sleeve-valve having a row of double-purpose ports, and a stationary part co-operating with said sleeve-valve having two separate rows of ports, the three rows of ports being arranged so that each sleeve-valve port co-operates successively with one port in each of the two rows of stationary ports but does not at any time interfere with any others of said stationary ports.

37. A multi-cylinder internal combustion engine, comprising a plurality of cylinders, pistons movable in the respective cylinders, and a sleeve-valve having a combined axial reciprocation and circumferential oscillation so that any point thereon travels in a closed curved path, said sleeve-valve being arranged to control both the inlet and exhaust of a plurality of cylinders, said sleeve-valve having a row of double-purpose ports for each cylinder.

der which it controls, and a stationary part co-operating with said sleeve-valve having two rows of ports for each such cylinder, the three rows of ports for each cylinder being arranged so that each sleeve-valve port co-operates successively with one port in each of the two associated rows of stationary ports but does not at any time interfere with any other of said stationary ports, the rows of ports for the different cylinders controlled by said sleeve-valve being displaced angularly from one another in said closed-curved path of travel by time-angles corresponding substantially to the time-angles between the firing points of said cylinders in the engine cycle.

38. A multi-cylinder internal combustion engine, comprising a plurality of cylinders, pistons movable in the respective cylinders, and a sleeve-valve having a combined axial reciprocation and circumferential oscillation so that any point thereon travels in a closed curved path, said sleeve-valve being arranged to control both the inlet and exhaust of a plurality of cylinders, said sleeve-valve having a double-purpose port for each cylinder which it controls, and a stationary part co-operating with said sleeve-valve having an inlet port and an exhaust port for each such cylinder, the three ports for each cylinder being arranged so that the sleeve-valve port co-operates successively with the two stationary ports, the stationary ports for the different cylinders controlled by said sleeve-valves being arranged in rows which are displaced angularly from one another in said closed-curved path of travel by time-angles corresponding substantially to the time-angles between the firing points of said cylinders in the engine cycle.

39. A multi-cylinder internal combustion engine, comprising a plurality of cylinders, pistons movable in the respective cylinders, and a sleeve-valve having a combined axial reciprocation and circumferential oscillation so that any point thereon travels in a closed curved path, a stationary part within said sleeve-valve and co-operating with it, said sleeve-valve being arranged to control both the inlet and exhaust of a plurality of cylinders, said sleeve-valve and said stationary part co-operating therewith having co-operating ports for controlling both the inlet and exhaust of each cylinder which said sleeve-valve controls, said ports including a stationary inlet port and a stationary exhaust port for each such cylinder, the stationary ports for the different cylinders controlled by said sleeve-valve being arranged in rows which are displaced angularly from one another in said closed-curved path of travel by time-angles corresponding substantially to the time-angles between the firing points of said cylinders in the engine cycle.

40. An internal combustion engine, com-

prising a cylinder having a cylinder head, a piston reciprocable in said cylinder, a sleeve-valve mounted in the cylinder head, a stationary core within said sleeve-valve, said core having a passage therein for connection to said cylinder, and said sleeve-valve being arranged to control the connection of said core-passage to said cylinder, and means for moving said sleeve-valve so that it has components of movement both to and fro along its axis and to and fro circumferentially. 70

41. An internal combustion engine, comprising a cylinder having a cylinder head, a piston reciprocable in said cylinder, a sleeve-valve mounted in the cylinder head, a stationary core within said sleeve-valve, said core having a passage therein for connection to said cylinder, and said sleeve-valve being arranged to control the connection of said core-passage to said cylinder, and means for moving said sleeve-valve so that it has components of movement both to and fro along its axis and to and fro circumferentially, 80 said two components of motion being combined so that a point on the sleeve-valve travels in a closed curved path. 85

42. An internal combustion engine, comprising a cylinder, a piston reciprocable therein, a curved sliding valving element having convex and concave surfaces and located apart from said piston, said piston being free from enclosure within said valving element, a member cooperating with the concave face of said curved valving element and having a passage therein, said valving element being arranged to control the connection between said passage and a port for said cylinder, and means for sliding said valving element with components of motion to and fro in two directions transverse to each other, 95 at least one of said components of motion being a rectilinear reciprocation. 100

43. An internal combustion engine, comprising a cylinder, a piston reciprocable therein, a curved sliding valving element having convex and concave surfaces and located apart from said piston, said piston being free from enclosure within said valving element, a member co-operating with the concave face of said curved valving element and having open space therein, said valving element being arranged to control the connection between both an inlet and an exhaust port for said cylinder and open space within said member, and means for sliding said valving element with components of motion to and fro in two directions transverse to each other, 110 at least one of said components of motion being a rectilinear reciprocation, said two components of motion being relatively arranged so that a point on the valving element travels in a closed curved path. 115

44. In an internal combustion engine, a cylinder, a piston, a sleeve-valve having a combined axial reciprocation and circumfer- 120

ential oscillation so that any point thereon travels in a closed curved path, said sleeve-valve being arranged to control both the inlet and exhaust of the cylinder, said sleeve-valve having two double-purpose ports, and 5 a stationary part co-operating with said sleeve-valve and having a plurality of exhaust ports and a plurality of inlet ports for said cylinder, each double-purpose port in the sleeve-valve being arranged to co-operate 10 successively with one exhaust port and one inlet port in the stationary part without interfering at any time with any other port in said stationary part.

45. A multi-cylinder internal combustion engine, comprising a plurality of cylinders, pistons movable in the respective cylinders, a sleeve-valve having a combined axial reciprocation and circumferential oscillation so 15 that a point thereon travels in a closed curved path, said sleeve-valve being arranged to control both the inlet and exhaust of a plurality of cylinders, said sleeve-valve having a row 20 of double-purpose ports for each cylinder 25 which it controls, and a stationary part co-operating with said sleeve-valve and having a plurality of inlet ports and a plurality of exhaust ports for each such cylinder, the ports for each cylinder being arranged so that each 30 sleeve-valve double-purpose port co-operates successively with an exhaust port and with an inlet port in said stationary part but does not at any time interfere with any others of the ports in said stationary part, the rows of 35 ports provided in said sleeve-valve for the different cylinders controlled by said sleeve-valve being displaced angularly from one another in said closed-curved path of travel by time-angles corresponding substantially 40 to the time-angles between the firing points of said cylinders in the engine cycle.

46. An internal combustion engine, comprising a cylinder, a piston reciprocable therein, a curved sliding valving element having convex and concave surfaces and located 45 apart from said piston, said piston being free from enclosure within said valving element, a member co-operating with the concave face of said curved valving element and having 50 open space therein, said valving element being arranged to control the connection between both an inlet and an exhaust port for said cylinder and open space within said member, and means for sliding said valving 55 element with port-controlling components of motion to and fro in two directions transverse to each other, said two components of motion being relatively arranged so that a point on the valving element travels in a 60 closed curved path.

47. An internal combustion engine, comprising a cylinder having a cylinder head, a piston reciprocable in said cylinder, a sleeve-valve free of cross-tubes mounted in the cylinder head on an axis transverse to the cyl-

inder axis and controlling a port of said cylinder, and means for driving said sleeve-valve with a combined axial reciprocation and circumferential oscillation so that any point thereon travels in a closed curved path. 70

48. An internal combustion engine, comprising a cylinder having a cylinder head, a piston reciprocable in said cylinder, a sleeve-valve free of cross-tubes mounted in the cylinder head on an axis transverse to the cylinder axis and controlling both an inlet port and an exhaust port of said cylinder, and means for driving said sleeve-valve with a combined axial reciprocation and circumferential oscillation so that any point thereon travels in a 75 80 closed curved path.

49. An internal combustion engine, comprising a cylinder having a cylinder head, a piston reciprocable in said cylinder, a sleeve-valve free of cross-tubes mounted in the cylinder head on an axis transverse to the cylinder axis and controlling all the ports of said cylinder, and means for driving said sleeve-valve with a combined axial reciprocation and circumferential oscillation so that any 85 90 point thereon travels in a closed curved path.

50. In an internal combustion engine, a cylinder, a piston, a sleeve-valve, a core 95 movably mounted concentrically within said sleeve valve and normally stationary in the operation of the engine, said core being provided with one or more gas passages, and means for moving said sleeve-valve with a combined axial reciprocation and circumferential oscillation to control the flow of gas 100 through said passage or passages.

51. The invention set forth in claim 50 with the addition that the sleeve-valve is disposed with its axis apart from the axis of 105 said cylinder.

In witness whereof, I have hereunto set my hand at Indianapolis, Indiana, this 11th day of May, A. D. one thousand nine hundred and twenty-six.

JULES HALTENBERGER.

CERTIFICATE OF CORRECTION.

Patent No. 1,756,684.

Granted April 29, 1930, to

JULES HALTENBERGER.

It is hereby certified that error appears in the printed specification of the above numbered patent requiring correction as follows: Page 6, line 108, claim 3, strike out the comma after "cylinder"; page 8, lines 88 and 100, claims 21 and 22 respectively, for the word "parts" read "ports"; and that the said Letters Patent should be read with these corrections therein that the same may conform to the record of the case in the Patent Office.

Signed and sealed this 13th day of May, A. D. 1930.

(Seal)

**M. J. Moore,
Acting Commissioner of Patents.**
